UNITED STATES PATENT OFFICE.

WILLIAM H. COLLIER, OF PAINESVILLE, OHIO.

SPLINT MACHINE.

Application filed October 24, 1921. Serial No. 510,079.

To all whom it may concern:

Be it known that I, WILLIAM H. COLLIER, a citizen of the United States, and a resident of Painesville, Lake County, State of Ohio, ⁵ have invented certain new and useful Improvements in Splint Machines, of which the following is a specification.

My invention is for a new and improved machine, entirely automatic in its operation, ¹⁰ for cutting splints from logs. In the old practice of cutting splints from veneer, the veneer was first cut from the log and sawed or cut lengthwise into strips of the required width. These two operations were usually ¹⁵ performed in one machine. It was then necessary for the workmen to transfer piles of these strips of veneer to a separate machine, commonly called a "clipper," in which a reciprocating knife clipped or cut ²⁰ the strips transversely into splints. That process required the use of at least two machines and entailed additional labor, with a corresponding increase in the cost of manufacture.

²⁵ It is the object of my present invention to overcome the foregoing and other objections by a machine which automatically performs the three functions of cutting veneer from a log, dividing the veneer lengthwise ³⁰ into strips of predetermined width and cutting the strips transversely into splints. As far as I am aware, I am the first to produce a commercially practical automatic machine of this kind, and I therefore claim broadly ³⁵ any construction embodying the basic features of my invention, as will later appear.

For the purpose of explaining the principle and advantages of my invention, I will refer to the accompanying drawings, which ⁴⁰ show an illustrative embodiment of my invention. In these drawings—

Fig. 1 is a longitudinal cross-section of a machine constructed in accordance with my invention;

⁴⁵ Fig. 2 is a plan view of the machine;

Fig. 3 is a transverse cross-section approximately on the broken line 3—3 of Fig. 1, looking in the direction of the arrows;

⁵⁰ Fig. 4 is a detached perspective view on an enlarged scale, showing how my new cutting mechanism cuts the veneer lengthwise into strips and crosswise into splints;

Fig. 5 is a detached view in elevation of

a modified form of splint-cutter in which the teeth are so arranged as to cut tapered splints;

Fig. 6 is an end view of Fig. 5 and

Fig. 7 illustrates diagrammatically how a strip of veneer is cut into tapered splints by the cutter shown in Figs. 5 and 6.

A log 1 is rotatably supported in the machine by any suitable means heretofore used in veneer-cutting machinery. I need not, therefore, describe in detail how the log is rotated. It is sufficient to say that the log is supported between a pair of chucks 2 (see Fig. 3), which are rotated at a proper speed from a suitable source of power, as will be understood. A knife 3 is arranged to cut veneer from the log as the latter is rotated in the direction of the arrow *a* in Fig. 1. The knife 3 is mounted on a frame or knife-bar 4, which is automatically adjustable as the log is cut down to keep the knife 3 in proper cutting position. As this is an old feature in veneer-cutting machinery, I need not go into any detail concerning it.

A roller 5, preferably of steel, presses against the rotating log along a line slightly in advance of the cutting edge of the knife, as shown in Fig. 1, and is rotated by this frictional contact at the surface speed of the log. The roller 5 is supported by a pair of slideable blocks 6 mounted in recesses 7 of side pieces or members 8 (see Fig. 3). The pressure of the roller 5 against the log is adjusted by a pair of bolts 9 mounted in lugs 10 of the supporting frame 11, to which the side members 8 are secured. To permit adjustment of the members 8 on the frame ⁸⁰ 11, these members are provided with elongated openings 12, through which pass bolts ⁸⁵ 13. The inner ends of the bolts 9 bear against the side pieces 8. To regulate the pressure of the roller 5 against the log, it ⁹⁰ is only necessary to loosen the bolts 13 and turn the bolts 9 in the right direction until the end pieces 8 have been shifted sufficiently toward or from the log. The bolts 13 are then tightened, whereby the end pieces 8 and roller 5 are locked in adjusted position.

The blocks 6 are provided with pins 14 on which are pivoted collars 15. A transverse shaft 16 carries a pair of cam disks ¹⁰⁵ 17, which fit in the collars 15. When the shaft 16 is turned in the direction of the ar-

row 6 in Fig. 1, the blocks 6 are bodily shifted toward the left (as viewed in Fig. 1), thereby carrying the pressure roller 5 away from the log. Any suitable means 5 may be used for turning the shaft 16, such as a handle diagrammatically indicated at 18 in Fig. 1. It should be understood that the operation of the shaft 16 has nothing to do with adjusting the pressure of the roller 10 5 against the log, but is for the purpose of moving the roller away from the log out of operative position, or against the log into operative position. The pressure of the roller 5 against the log is regulated by the bolts 15 9, as previously described.

This roller presents a moving surface to the log and may, therefore, be driven with less power than the stationary bar of the prior machines. The roller 5 does not tend 20 to injure the fibers and produces veneer of uniform smoothness. It will be understood that as the knife 3 is automatically adjusted in its relation to the rotating log during the cutting process, the pressure roller 5 moves 25 along with the knife. This automatic adjustment of the pressure roller simultaneously with the knife 3 is not part of my present invention and may be carried out in the same way as the automatic adjustment 30 of the pressure bars in the prior veneer machines, or in any other way.

As the veneer is cut from the rotating log by the knife 3, it advances over a table 19. In Fig. 1 the veneer is indicated at 20. 35 In usual practice, the veneer is about twenty-four inches wide, although machines may be constructed to receive logs of different lengths. The table 19 is provided with a trap-door 21 hinged at 22 to the frame or 40 knife-bar 4. When the trap-door 21 is in normal position, it allows the veneer 20 to pass over the table 19 to the front of the machine. When the trap-door 21 is dropped, as indicated roughly by the dotted lines 45 21', the veneer passes through the opening 23. The purpose of the trap-door 21 is to keep faulty or waste material from the splint cutters at the front of the machine. As logs are put into the machine with the bark on, 50 the first cuttings are waste material. When this begins to come off the log, the attendant opens the trap-door 21 and allows the material to pass out through the opening 23. As soon as good veneer begins to appear 55 from between the roller 5 and the knife 3, the attendant closes the trap-door 21 and allows the veneer to pass over the table 19 to the cutters, which I will presently describe. Any suitable means may be employed for operating the trap-door 21. In 60 Fig. 1, I have shown a link 24 connecting the trap-door 21 with an arm 25 secured to a shaft 26, which may be operated in any convenient way. The trap-door 21 preferably 65 has a cutting edge 27 at its free end.

The table 19 is provided with a strip of steel 28 having a cutting edge 29. The cutting edges 27 and 29 co-operate to cut the veneer when the trap-door 21 is swung into closed or normal position, thus giving the 70 veneer a clean front edge.

I will now describe the form of mechanism shown in the drawings for cutting the veneer lengthwise into strips and cutting the strips crosswise into splints. At the front 75 end of the machine is rotatably mounted a transverse shaft 30 supported in suitable bearings 31, as shown in Figs. 2 and 3. On the shaft 30 are fixed a plurality of circular saws 32 and a plurality of rotary cutters 80 33. In the particular construction shown, there are five saws and six cutters. In practice, where two-foot logs are used, there will be eleven saws to cut the veneer into twelve strips of about two inches width 85 each, and there will be a cutter for each strip. Lack of space on the drawing sheets has prevented me from showing this arrangement, but it will be clearly understood. A bushing 34 and nut 35 (see Fig. 3) hold 90 the saws 32 and cutters 33 firmly clamped on the shaft. The distance between the outer edges of the two outer cutters is approximately the width of the veneer, and the width of each cutter is determined by 95 the width of splint to be cut. Suitable means, such as keys or splines 36 (see Figs. 1 and 4), lock the saws and cutters to the shaft 30, so that these parts always rotate as a unit. The table 19 is provided at the front 100 end with a strip of steel 37 having a knife edge 38. The strip 37 has slots 39 to receive the teeth of the saws 32, which are of slightly greater diameter than the splint cutters 33, so that the veneer is cut lengthwise into strips in advance of the cutters 33. The action of the saws 32 and cutters 33 is best illustrated in Fig. 4. As the veneer 105 20 advances, the saws 32 cut the same lengthwise into strips in advance of the cutters 33. Then, as the veneer moves against the cutters 33, the knife-edges 33' of the cutters cut the strips of veneer transversely into 110 splints, one of which is shown at 40 in Fig. 4. In practice, if the machine is used for cutting match splints of standard size, the knife-edges 33' of the cutters 33 are so spaced that the successive teeth of the cutters will cut off splints of about one-tenth 115 of an inch in width. In that case the thickness of the veneer will also be about the same. I mention these figures merely because they are the approximate dimensions of certain types of matches sold in the market. The shape and width of the splints will be determined by the form and arrangement of the teeth on the cutters 33. The cutting edges 33' of the cutters and the cutting edge 30 of the table 19 in effect form shears 120 which clip the splints off clean, leaving no 125 130

rough edges or splinters. While at the present time I prefer to mount the saws 32 on the same shaft as the splint cutters 33, because of the compactness of the arrangement, it is obvious that the veneer may be cut into strips in advance of the splint cutters by any means suitable for that purpose.

I have provided means for driving the cutter shaft 30 at the surface speed of the log 1, so that the speed of the saws and cutters will always be in proportion to the rate of feed of the veneer. It is obvious that, as the log 1 is cut away, the surface speed gradually decreases and the rate of feed of the veneer is correspondingly reduced. For this reason the speed of operation of the saws 32 and splint cutters 33, or at least that of the cutters 33, must be reduced in proportion to the decreasing rate of feed of the veneer, in order to produce splints of substantially uniform width. This automatic regulation of the speed of the cutter shaft 30, in accordance with the continuously changing surface speed of the rotating log, is accomplished by connecting the shaft 30 with the pressure roller 5. I have already explained that the speed of the roller 5 is always the same as the surface speed of the rotating log. Therefore, by driving the shaft 30 from the roller 5, or otherwise governing the speed of that shaft in accordance with the changing speed of the roller, the splint cutters 33 will cut splints of approximately the same width, without regard to the varying rate of feed of the veneer. The particular form of driving or controlling connection between the pressure roller 5 and the cutter shaft 30 is not material in the broad aspect of my invention. In the drawings I have shown a sprocket wheel 41 fixed on the shaft which carries the roller 5. Another sprocket wheel 42 is fixed near one end of a transverse shaft 43 suitably mounted in the framework of the machine, as best shown in Fig. 3. The sprocket wheels 41 and 42 are connected by a chain or other driving member 44. A large internal gear 45 is fixed upon the shaft 43 and the teeth of this gear are in mesh with a pinion 46 rigidly mounted on the projecting end of the cutter shaft 30, as may be seen in Fig. 3. In this way the shaft 30 is permanently connected with the pressure roller 5, which derives sufficient power from the rotating log to operate the shaft 30. The gear ratio between the roller 5 and shaft 30 is such that the teeth of the cutters 33 clip off splints of a predetermined width. The speed at which the cutters 33 shall be operated and the spacing of the axial cutting edges 33' to produce splints of a certain width, are matters within the skill of the mechanic.

The rotary cutting mechanism composed of the saws 32 and splint cutters 33 is pref-

erably enclosed in a casing, which may conveniently be formed by a casting C having a cover 47 hinged at 48. The cover 47 has a rearwardly projecting lip or flange 49, which forms a beveled undersurface 50 when the cover is closed, as shown in Fig. 1. The beveled surface 50 acts as a guide for the forward edge of the veneer. The cover 47 is readily swung back to expose the mechanism within.

The casting C has chambers or passages 51 formed by partitions 52. As seen in Fig. 3, the chambers 51 are in alignment with the splint cutters 33 and connect with a common reservoir 53. As the splints are cut off by the cutters 33, they drop through the chambers or passages 51 into the common reservoir 53, from which they are removed in any suitable way—as by a fan 54. If the splints are used for matches, they are drawn or blown from the reservoir 53 into an impregnation tank.

It sometimes happens that veneer is not perfect throughout its entire width as it comes from the log, due to knots or other faults in the wood. In order to separate the faulty splints from the good ones, I provide each of the chambers 51 with a deflector, which the attendant operates to keep faulty splints out of the reservoir 53. Referring to Fig. 1, it will be seen that each of the chambers 51 has an opening 55 in the front wall, which is normally closed by a deflector 56 pivoted at 57 and provided with a handle 58. The normal position of each deflector is that shown in full lines in Fig. 1. When the attendant sees an imperfection in the veneer as it moves toward the cutters, he lifts the handle 58 of the deflector corresponding in position to the imperfect portion of the veneer. This throws the deflector into the position indicated by the dotted lines 56' in Fig. 1, thereby shutting off that particular chamber 51 from the reservoir 53 and allowing the faulty splints to slide down the inclined deflector 56 into a waste chamber 59. An exhaust or blower fan 60 may be used to remove the waste splints from the chamber 59. In this way each strip of veneer is controlled separately, thus reducing the waste to a minimum.

In order to get tapered splints, such as are used for toothpicks, it is only necessary to provide a splint cutter in which the cutting edges of the teeth are arranged at alternate reverse angles relatively to the axis of the cutter. Such a cutter is shown in Figs. 5 and 6, from which it will be seen that the cutting edges of the teeth are arranged in two sets: The cutting edges 33^a incline in one direction and the cutting edges 33^b incline in the opposite direction relatively to the axis of the cutter. The cutting effect of the teeth 33^a and 33^b is indicated by the dotted lines 2^a and 2^b on the sheet of veneer.

shown in Fig. 7, from which it will be seen that there is no waste of material in cutting tapered splints by this new form of cutter.

In the broad aspect of my invention, I am not restricted to the details of construction herein set forth. It is obvious that the fundamental principles involved in my new automatic splint-cutting machine may be mechanically carried out in various forms of construction without departing from the scope and spirit of my invention as defined in the appended claims.

What I claim is:

1. In an automatic splint machine, means for cutting veneer from a rotating log, a table over which the veneer travels forwardly, a plurality of rotating saws mounted along the front edge of said table to cut the veneer lengthwise into strips of predetermined width, and rotary knives for cutting the strips transversely into splints.

2. In an automatic splint machine, means for cutting veneer from a rotating log, a table over which the veneer travels forwardly, the front edge of said table being provided with spaced slots, a plurality of rotary saws mounted along the front edge of said table and extending into said slots to cut the veneer lengthwise into strips of predetermined width, and rotary knives for cutting the strips transversely into splints.

3. In an automatic splint machine, means for cutting veneer from a rotating log, a table over which the veneer travels forwardly, the front edge of said table being provided with spaced slots, a plurality of rotary saws mounted along the front edge of said table and extending into said slots to cut the veneer lengthwise into strips of predetermined width, and means for cutting the strips transversely into splints.

4. In an automatic splint machine, means for cutting veneer from a rotating log, a rotary shaft, a plurality of spaced circular saws mounted on said shaft to cut the veneer lengthwise into strips, and a plurality of cylindrical members mounted on said shaft between the saws and having cutting edges arranged to cut the strips transversely into splints.

5. In an automatic splint machine, a rotary veneer-cutting device comprising a plurality of spaced circular saws adapted to cut the veneer lengthwise into strips, and circularly arranged knives mounted between said saws to cut the strips transversely into splints.

6. In an automatic splint machine, means for cutting veneer from a rotating log, a table over which the veneer travels forwardly, a rotary shaft arranged in front of the table and substantially parallel with the front edge thereof, a plurality of spaced circular saws mounted on said shaft to cut the veneer lengthwise into strips, and a plurality

of rotary knives mounted on said shaft between the saws to cut the strips transversely into splints, the teeth of said saws extending radially beyond the cutting edges of said knives.

7. In an automatic splint machine, a unitary rotary structure forming a combined veneer-dividing and splint-cutting device, said device comprising a rotary shaft, a plurality of saws fixed on said shaft and spaced apart for dividing the veneer lengthwise into strips, and a plurality of cylindrical cutters mounted on said shaft between said saws, said cutters having integral teeth arranged to cut the strips transversely into splints.

8. In an automatic splint machine, means for cutting veneer from a rotating log, a table over which the veneer travels forwardly, and rotary mechanism mounted along the front edge of said table and extending above and below the table for cutting the veneer lengthwise into strips and cutting the strips transversely into splints.

9. In an automatic splint machine, means for cutting veneer from a rotating log, a table over which the veneer travels forwardly, a knife edge mounted transversely at the outer end of said table, said knife edge being provided with spaced slots extending rearwardly, a transverse shaft mounted in front of the table, rotary saws fixed on said shaft and having their teeth extending into said slots to cut the veneer lengthwise into strips, and cutters mounted on said shaft between said saws to cooperate with the knife edge of said table for cutting the strips transversely into splints.

10. In an automatic splint machine, means for cutting veneer from a rotating log, a table over which the veneer travels forwardly, a plurality of rotating saws mounted along the front edge of said table to cut the veneer lengthwise into strips of predetermined width, rotary knives for cutting the strips transversely into splints, and means for rotating said saws and knives in synchronism with the surface speed of the rotating log.

11. In an automatic splint machine, means for cutting veneer from a rotating log, a table over which the veneer travels forwardly, a plurality of rotating saws mounted along the front edge of said table to cut the veneer lengthwise into strips of predetermined width, rotary knives for cutting the strips transversely into splints, and means actuated by the log itself for operating said saws and said knives.

12. In an automatic splint machine, means for supporting a log in position to be rotated, a knife arranged to cut veneer from the rotating log, rotary saws for cutting the veneer lengthwise into strips of predetermined width, rotary knives for cutting

the strips transversely into splints, a roller arranged to press lengthwise against the rotating log so as to be driven continuously at the surface speed of the log, and means for rotating said saws and knives in unison with said roller.

13. In an automatic splint machine, means for supporting a log in position to be rotated, a knife arranged to cut veneer from the rotating log, a rotary shaft, a plurality of spaced circular saws mounted on said shaft to cut the veneer lengthwise into strips, a plurality of cylindrical members mounted on said shaft between the saws and having cutting edges arranged to cut the strips transversely into splints, and means for rotating said shaft in synchronism with the surface speed of the log.

14. In an automatic splint machine, means for supporting a log in position to be rotated, a knife arranged to cut veneer from the rotating log, a rotary shaft, a plurality of spaced circular saws mounted on said shaft to cut the veneer lengthwise into strips, a plurality of cylindrical members mounted on said shaft between the saws and having cutting edges arranged to cut the strips transversely into splints, a roller arranged to press lengthwise against the rotating log so as to be driven continuously at the surface speed of the log, and driving connections between said shaft and said roller.

15. In an automatic splint machine having means for cutting veneer from a rotating log, rotary mechanism for cutting the veneer lengthwise into strips and cutting the strips transversely into splints, and means for operating said mechanism in synchronism with the surface speed of the log.

16. In an automatic splint machine having means for cutting veneer from a rotating log, rotary mechanism for cutting the veneer lengthwise into strips and cutting the strips transversely into splints, a roller arranged to press against the rotating log so as to be driven continuously at the surface speed of the log, and driving connections between said roller and said mechanism.

17. In an automatic splint machine, means for cutting veneer from a rotating log, means for cutting the veneer lengthwise into strips of predetermined width, means for cutting the strips transversely into splints, a discharge passage in alignment with the splint-cutting means of each strip to receive the splints from that strip, and means for controlling each of said passages separately.

18. In an automatic splint machine, means for cutting the veneer lengthwise into strips, a plurality of rotary cutting members adapted to cut the strips transversely into splints, a normally open compartment for

each member to receive the splints, means associated with each compartment for preventing the passage of splints therethrough, and a common reservoir with which all of said compartments communicate.

70

19. In an automatic splint machine, means for cutting veneer from a rotating log, means for cutting the veneer lengthwise into strips, a plurality of rotary cutting members adapted to cut the strips transversely into splints, a compartment for each member to receive the splints, a common reservoir with which all of said compartments normally communicate, a second reservoir, and a deflector in each compartment for diverting splints into said second reservoir.

75

20. In an automatic splint machine, a plurality of rotary cutters for cutting splints from strips of veneer, a vertical chamber beneath each rotary cutter, a reservoir in which all of said chambers terminate to receive the splints, and means for controlling each chamber separately to direct splints into or deflect them out of said reservoir.

80

21. In an automatic splint machine, means for cutting veneer from a rotating log, a table over which the veneer travels forwardly, rotary saws so mounted that the teeth thereof project above and below the surface of said table to cut the veneer lengthwise into strips, and rotary knives arranged to cooperate with the front edge of said table to cut the strips transversely into splints.

85

22. In an automatic splint machine, means for cutting veneer from a rotating log, a table over which the veneer travels forwardly, rotary saws so mounted that the teeth thereof project above and below the surface of said table to cut the veneer lengthwise into strips, and rotary knives arranged to cooperate with the front edge of said table to cut the strips transversely into splints, the cutting edges of said knives being arranged at alternately reversed angles relatively to the axis of rotation thereof, whereby said knives cut tapered splints.

95

23. As a new article of manufacture for use in splint-cutting machines, a cylindrical cutter provided with integral teeth projecting in a substantially tangential direction from the body of the cutter, said teeth terminating in cutting edges arranged at alternately reversed angles relatively to the axis of the cutter.

100

24. In an automatic splint machine, means for cutting veneer from a rotating log, a rotary shaft, and a rotary cutting device mounted on said shaft, said device having teeth to cut the veneer lengthwise into strips and teeth arranged to cut the strips transversely into splints.

110

25. In a veneer-cutting machine, means

115

120

125

130

- for cutting veneer from a rotating log, a table over which the veneer is fed, there being a space or passage below the table, a trap-door in said table for normally closing 5 said passage, and means for operating said trap-door to control the travel of veneer over said table or into said passage.
26. In an automatic splint machine, a rotary shaft, a plurality of saws on said shaft 10 for cutting the veneer lengthwise into strips, and a plurality of cylindrical cutters mounted on said shaft between said saws, said cutters having integral teeth arranged to cut tapered splints transversely from the front 15 edges of the strips.
27. In an automatic splint machine, means for cutting the veneer lengthwise into strips, a table over which the veneer travels, and a plurality of cylindrical cutters mounted 20 along the front edge of said table so as to extend above and below the surface thereof, said cutters having integral teeth arranged to cut tapered splints transversely from the front edges of the strips.
28. In a veneer-cutting machine, means 25 for cutting veneer from a rotating log, a table over which the veneer is fed, a trap-door in said table, and means for controlling
- said trap-door, said table and said trap-door having co-operating knife-edges to cut 30 the veneer when the trap-door is closed.
29. In a veneer-cutting machine, means for cutting veneer from a rotating log, a table over which the veneer is fed, a section 35 of said table being hinged to form a trap-door, and means for swinging said trap-door into open and closed positions to control the travel of veneer over said table or through said trap-door.
30. In a veneer cutting machine, means 40 for cutting veneer from a rotating log, a table over which the veneer is fed, a section of said table being hinged to form a trap-door, and means for swinging said trap-door into open and closed positions, 45 said table and said trap-door having co-operating knife edges to cut the veneer when the trap-door is closed.
31. In an automatic splint machine having means for cutting veneer from a rotating 50 log, rotary mechanism for cutting the veneer lengthwise into strips and cutting the strips transversely into splints, and a rotary shaft on which said mechanism is mounted as a unit.

WILLIAM H. COLLIER.
